(57) **CLAIM**

The ornamental design for a portable hunter's chair, as shown and described.

DESCRIPTION

FIG. 1 is a frontal isometric view of the new chair;

FIG. 2 is a side elevational view thereof, the opposite side comprising a mirror image;

FIG. 3 is an end elevational view, the opposite end comprising a mirror image;

FIG. 4 is a top plan view thereof;

FIG. 5 is a bottom isometric view; and,

FIG. 6 is an enlarged, fragmentary isometric view of a typical corner region.
